UNITED STATES PATENT OFFICE.

WILLIS S. JONES, OF CHICAGO, ILLINOIS.

TIE-PLATE FOR RAILWAYS.

SPECIFICATION forming part of Letters Patent No. 754,654, dated March 15, 1904.

Application filed October 23, 1902. Serial No. 128,406. (No model.)

To all whom it may concern:

Be it known that I, WILLIS S. JONES, a citizen of the United States, and a resident of the city of Chicago, in the county of Cook and State of Illinois, have invented certain new and useful Improvements in Tie-Plates for Railways; and I do hereby declare that the following is a full, clear, and exact description of the same, reference being had to the accompanying drawings, and to the letters of reference marked thereon, which form a part of this specification.

This invention relates to tie-plates for railways of that class in which one or more longitudinal flanges are provided on the under side of the plate which engage the grain of the tie and act to compress the same beneath the plate and to more firmly hold the plate in position. Millions of tie-plates of various kinds are used annually in this country, the object of such plates being to afford a positive bearing-surface for the rail and to prevent brooming or cutting of the tie, due to the impact of the rails thereon during the passage of trains. Heretofore such plates have been made much heavier than has been necessary, or if attempts have been made to lighten the plates the result has usually been to materially decrease the strength of the same. This, while affording a profit to the manufacturer, seriously endangers the efficiency and safety of the construction.

The object of this invention is to provide a tie-plate of such construction as to afford maximum strength with minimum weight, at the same time affording improved means auxiliary to the usual spikes for gripping the plate to the tie.

The invention consists in the matters herein-after described, and more fully pointed out and defined in the appended claims.

In the drawings, Figure 1 is a perspective view of a transverse section of a device embodying my invention. Fig. 2 is a perspective view of the plate, showing the same inverted. Fig. 3 is a fragmentary longitudinal section of the same. Fig. 4 is a fragmentary transverse section thereof.

As shown in said drawings, the body of the plate comprises a broad bar of metal, prefer-

ably rolled and providing a comparatively broad plate and having alternately-arranged upper and lower longitudinal flat bearing-surfaces A A' A² and B B' B² B³, respectively, forming a plurality of wave-like corrugations, 55 which alternately afford a bearing upon the tie and a bearing for the rail-base, with intermediate grooves or channels between the bearings on each side of the plate, as shown.

Each of the lateral margins of the plate are 60 turned downwardly, as shown in Figs. 1 and 4, providing lateral side flanges c c, the surface of which from the lower edge curve inwardly to meet the plane of the under surface of the ribs or bearing-surfaces B³. At the longitudinal 65 center of the plate and located below the bearing A' a comparatively broad sharp flange C is provided, which serves to engage in the wood of the tie beneath the middle of the plate, compressing the same laterally and positively engaging the plate with the tie. As shown, a comparatively narrow longitudinal flange is provided on the under side of the plate, at or near each of the bends of the same and indicated, respectively, by c', c², and c³. Said flanges c, c', 70 c², and c³ are all approximately of the same width, as shown in Fig. 4, and serve to positively compact between the same the wood or other material of the tie, affording a better bearing-surface for the plate thereon and aiding in affording positive engagement with the tie. One or more of said flanges are of less 75 length than the length of the plate, which projects beyond the ends of the same at each end sufficiently to afford a comparatively broad 80 lower bearing-surface at each end of the plate.

Each of the concave channels in the under side of the plate are closed at the ends and beyond the ends of the longitudinal flanges by the downwardly-turned sharp claws D d, of 90 which the claw D is opposite or adjacent to the ends of the flange C, closing the central channel on each side of said flange and between the flanges c' c'. The flanges d are located adjacent to the ends of and between the flanges c² c³, closing the ends of the channel between said flanges. Disposed along the length of the groove or channels beneath the ribs or bearing A and A² are provided a plurality of 95 downwardly-turned transverse claws on the 100

under side of the plate, (indicated by d'), which are similar to the claws D and d and extend below the plane of the under surface of the plate and engage the tie transversely of the grain. Said flanges D d d' are provided with sharp chisel-shaped edges extending transversely of the grain of the tie, and the faces of the same are directed against the greatest thrust on the plate, or, in other words, toward 10 the outer end of the same and are flat and approximately perpendicular with the plane of the plate. Spike-holes in any desired number are provided through the plate, preferably passing through the upwardly-turned ribs, 15 bearings, or bars A and A², as shown in Figs. 1 and 2 and 4.

The operation is as follows: The tie-plate is bedded upon the tie, with the claws of transverse flanges D d directed toward the adjacent 20 ends of the tie, or, in other words, toward the outer side of the rail to be supported thereon and all of the flanges positively engaged in the tie. Any slight crack or seam formed in the tie at the ends of the longitudinal flanges is positively closed by the transverse flanges D d and the overlapping ends of the tie-plate, so that dirt or moisture cannot 25 find its way therein. Owing to the bends or corrugations in the plate much less thickness 30 and weight of metal need be employed to obtain a required strength, as the longitudinal flanges serve to greatly strengthen the plate at the bends, forming, in effect, at each bend a longitudinal truss. It is also obvious that 35 each of the transverse flanges D d d' serve as a transverse brace or truss across the grooves or channels in the under side of the plate, the metal being displaced downwardly in punching while remaining integrally connected with 40 the metal on each side of the same. The plate owing to said transverse flanges is rendered practically as strong transversely though very much lighter than plates constructed as heretofore.

45 Obviously the plates may be made of any desired width, and the number, size, and disposition of flanges may be varied to suit varying conditions, and many details of construction may be varied without departing from the 50 principles of this invention.

I claim as my invention—

1. A plate of approximately uniform thickness waved or corrugated transversely to provide a plurality of lower flat bearing-surfaces 55 for engagement on the tie and upper flat bearing-surfaces arranged alternately therewith to support the rail, and one or more longitudinal flanges on the under side of the plate of a length less than the length of the plate.

60 2. An article of manufacture comprising a plate of metal formed to provide a plurality of lower flat bearing-surfaces in approximately the same plane alternating with a plurality of upper flat bearing-surfaces, said plate having 65 an integral downwardly-directed sharp flange

shorter than the corresponding dimension of the plate.

3. An article of manufacture comprising a plate of metal formed to provide a plurality of lower flat longitudinal bearing-surfaces in approximately the same plane alternating with a plurality of upper flat bearing-surfaces slightly raised above the same, said plate having an integral, central downwardly-directed sharp flange extending longitudinally of the 75 plate and shorter than the corresponding dimension of the plate.

4. An article of manufacture comprising a plate of metal comprising a plurality of flat, longitudinal upper bearing-surfaces and alternate downwardly-directed bearing-surfaces, a plurality of flanges on the under side of the plate extending longitudinally thereof and in length shorter than the plate, and a plurality of transverse flanges on the under side thereof 85 having their faces directed toward one end of the plate.

5. A plate of metal rolled to provide on its opposite faces alternately-arranged flat bearing-faces and concave grooves or gutters separating said faces, and a relatively short longitudinal flange located near each of the bends in the plate.

6. A plate of metal rolled to provide on its opposite faces alternately-arranged flat bearing-faces and concave grooves or gutters, and a relatively short longitudinal flange located near each of the bends in the plate and a transverse flange at the end of the longitudinal flange.

7. A tie-plate comprising a plate of metal having raised flat bearing-surfaces and intermediate grooves or gutters arranged alternately on opposite sides of the plate, a central downwardly-directed flange and a longitudinal flange parallel therewith on each side of said central flange and located at the bends in the plate, the ends of the plate projecting beyond said flanges, and downwardly-directed transverse flanges positioned to close the ends 110 of the gutters on the under side of the plate.

8. A tie-plate comprising a plate of metal having raised flat bearing-surfaces and intermediate grooves or gutters arranged alternately on opposite sides of the plate, a central 115 downwardly-directed flange and a longitudinal flange parallel therewith on each side of said central flange and located at the bends in the plate, the ends of the plate projecting beyond said flanges, and downwardly-directed transverse flanges positioned to close the ends of the gutters on the under side of the plate, and other transverse flanges intermediate of the ends of the plate.

9. An article of manufacture an apertured plate formed to provide transverse wave-like flat-topped corrugations presenting on opposite sides of the plate alternately-disposed bearing-surfaces and concave gutters or grooves, flanges located along the bends of 130

the plate on the under side thereof, a central longitudinal flange, transverse flanges closing the ends of the gutters on the under side of the plate, the ends of the plate extending beyond the longitudinal flanges and affording bearing-surfaces beyond the ends thereof.

10. A tie-plate comprising a transversely-corrugated plate apertured near the ends to receive spikes and corrugated transversely to provide alternately-arranged flat upper and lower bearing-surfaces, and upper and lower alternately-arranged longitudinal grooves or gutters, a central sharp flange located in one of the gutters in the under surface, parallel flanges of smaller size located on each side of the central flange at the bends in the plate, a lateral flange at each edge of the plate and transverse flange disposed at the ends of the gutters on the under side of the plate and intermediate of the ends thereof and presenting approximately flat resisting-faces against longitudinal thrust and serving as a transverse brace or truss for the plate.

11. A tie-plate comprising a plate of metal apertured to receive spikes and corrugated transversely, a plurality of longitudinal sharp flanges on the under side of the plate disposed one at each edge of the plate and one at each of the bends therein and a central broad sharp flange located intermediate of adjacent bends in the plate.

12. A tie-plate comprising a plate of metal apertured to receive spikes and corrugated

transversely, a plurality of longitudinal sharp flanges on the under side of the plate disposed one at each edge of the plate and one at each of the bends therein and a central broad sharp flange located intermediate of adjacent bends in the plate, the ends of the plate projecting beyond the longitudinal flanges and affording a bearing on the tie beyond said flanges.

13. A corrugated tie-plate of rolled metal apertured to receive spikes and one or more longitudinal downwardly-directed flanges thereon shorter than the plate and means adapted to prevent an end thrust of the plate.

14. A rolled tie-plate, corrugated to provide upper and lower alternate bearing-surfaces, flanges disposed along the bends of the plate and beyond which the ends of the plate project and means adapted to prevent longitudinal movement of said plate.

15. A rolled tie-plate corrugated and provided with flanges on the under side thereof shorter than the corresponding dimension of the plate and sharp flanges arranged between and at right angles with the first-named flanges the edges and ends of the plate projecting beyond all of the flanges.

In testimony whereof I have hereunto subscribed my name in the presence of two subscribing witnesses.
